CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

HIGH-VOLTAGE DISCONNECTING-SWITCH.

1,385,977.

Specification of Letters Patent.

Patented Aug. 2, 1921.

Application filed May 7, 1919. Serial No. 295,313.

To all whom it may concern:

Be it known that I, CHRISTIAN AALBORG, a citizen of the United States, and a resident of Pittsburgh, in the county of Allegheny and State of Pennsylvania, have invented a new and useful Improvement in High-Voltage Disconnecting-Switches, of which the following is a specification.

My invention relates to switches for electrical circuits and particularly to high-potential disconnecting switches.

One object of my invention is to provide a device of the above indicated character that shall so comprise a single rigid insulating pillar as to simplify its structure and facilitate its installation with respect to a transmission line.

Another object of my invention is to provide a high-potential disconnecting switch that shall be economical to manufacture, rugged and durable in construction and effective in operation.

Another object of my invention is to provide a high-potential disconnecting switch in which a pivoted switch arm shall be mounted at the top of a transmission-line tower and extend to a coöperating contact member, on a transmission-line conductor, at some distance from the tower.

In practising my invention, I provide, at the top of a transmission-line tower or other support, a vertically-projecting built-up insulating pillar having, pivoted at its upper end, an elongated switch arm for coöperation with a contact-terminal member that is mounted on a transmission-line conductor and remotely disposed with respect to said tower and said pillar. I also provide means whereby said pillar may be turned about its axis to actuate the switch arm.

Figure 1 of the accompanying drawings, is a side elevational view of a disconnecting switch embodying my invention, showing portions of a supporting tower and the transmission lines associated therewith; Fig. 2 is an end elevational view of the device shown in Fig. 1, and Fig. 3 is a detail sectional view of a portion of my improved device.

In general, my device comprises a longitudinally-rigid insulating pillar 1 disposed at the top of a transmission-line tower 2 and having, at its upper end, a hooded member 3 from which conductors 4 and a switch member 5 extend to points beyond the outer ends of two sets of strain insulators 6 and 7 that

are interposed between the tower 2 and the adjacent ends of two aligned conductors 8.

The member 3, which constitutes a weather-proof bearing member for a worm 9, that is rigidly and coaxially related to the pillar 1, has bearing portions 10 for a shaft 11 to which a worm wheel 12 is rigidly secured, as by a key 13.

Lever arms 14, exterior to the member 3 and rigidly secured to the ends of the shaft 11, are relatively movably attached to rods 15 that constitute parts of the switch member 5. The rods 15 are secured, in any suitable manner, as by a nut-and-eye connection 16, to conducting rods or arms 17 that are pivoted adjacent the upper ends of the conductors 4, to depending portions 18 of the member 3 and coöperate with a stationary contact-terminal member 19 and horn-gap projections 20, at the outer end of the insulator set 7.

The pillar 1 has a rigidly-related shaft 21 depending from the lower end thereof that is rotatably mounted in bearing members 22 and 23 on the tower 2. The lower end of the rod 21 is provided with a hand wheel 24 by means of which the pillar 1 may be rotated to actuate the worm 9 and the worm wheel 12 to disconnect the switch member 5 from the terminal member 19 and move it to its open position, shown by the dotted lines in Fig. 1.

The members 4 serve as mechanical supporting means for the parts 6 and 8 and also as conductors for current from the conductor 8, at the outer end of the insulator set 6, to the arms 17.

Inasmuch as the tower 2, the insulator sets 6 and 7 and the conductors 4 and 17, or their equivalents, would be present in an ordinary transmission support of this kind, where it did not constitute a switch, it is seen that to construct a disconnecting switch thereof requires a minimum of extra material. The device is simple in construction, effective in operation and requires the use only of a single rigid pillar.

While I have shown and described a particular form of my invention, changes may be effected therein without departing from the spirit and scope thereof, as set forth in the appended claims.

I claim as my invention:

1. A high-potential disconnecting switch comprising a main supporting structure, a

- plurality of sets of series-related strain insulators attached thereto, a turnable insulating pillar mounted by one end on said structure, a relatively-movable cap member disposed at the other end of said pillar and constituting a bearing therefor, rigidly-mounted conductors, constituting supporting members, extending from the outer end of one of said sets of strain insulators to said 10 cap member, a worm secured to, and movable with, said pillar, a worm wheel meshing with said worm and supported by said cap member, a lever arm rigidly secured to said worm wheel, a terminal member at the 15 outer end of another of said sets of strain insulators, a pivoted switch arm connected to said rigidly-mounted conductors, at said cap member and extending to said terminal member, and a rod connecting said pivoted 20 arm to said lever arm.
2. A high-potential disconnecting switch comprising a supporting structure, longitudinal insulating structures projecting oppositely therefrom, a longitudinal insulating 25 pillar projecting from said supporting structure at substantially right angles to said insulating structures, a member connected to the outer ends of one of said insulating structures and said pillar, and relatively- 30 movable means connecting said connecting member to the outer end of the other of said insulating structures.
3. A high-potential disconnecting switch comprising an insulating structure of substantially inverted T-shape and conducting 35 members extending diagonally between the outer ends of the legs thereof, one of said members constituting a movable switch arm.
4. A high-potential switch comprising a 40 single rigid insulating pillar, a flexible insulating structure secured adjacent thereto and extending therefrom, a terminal member remotely disposed with respect to the pillar on said structure and a movable switch 45 arm extending between said pillar and said terminal member.

5. A high-potential switch comprising an insulating pillar, a flexible insulating structure extending outwardly from the base thereof, a terminal at the outer end of said 50 flexible structure and a movable switch arm extending between said terminal and the outer end of said pillar.

6. A high-potential switch comprising an insulating pillar, a flexible insulating structure extending outwardly therefrom, a terminal at the outer end of said flexible structure, a movable switch arm extending between said pillar and said terminal and means for operating the switch arm through 60 the pillar.

7. A high-potential switch comprising an insulating pillar, a flexible insulating structure extending outwardly therefrom, a terminal attached to said flexible structure, a 65 movable switch arm extending between said pillar and said terminal and means for operating the switch arm through the pillar.

8. In a high-potential switch, the combination with a line conductor and a rigid 70 supporting structure therefor, of an insulating member on the supporting structure, a flexible insulating structure suspended between the supporting structure and said conductor for supporting the latter, a terminal member for the conductor disposed adjacent to the outer end of the flexible structure, and a movable switch arm extending 75 between said insulating member and said terminal member.

9. In a high-potential switch, the combination with a suspended conductor, of a single insulating supporting structure for one end of the conductor, a terminal member for the conductor suspended in spaced relation to the supporting structure, and a movable switch arm extending between said structure and said terminal member.

In testimony whereof, I have hereunto subscribed my name this 23d day of April, 90 1919.

CHRISTIAN AALBORG.
